2,194,094

MAGNETIC DECOMPOSING AND REASSEMBLING TELEVISION SYSTEM

Howard J. Murray, New York, N. Y.

Application August 18, 1936, Serial No. 96,579

8 Claims. (Cl. 178—6)

A general object of my invention is to provide a light decomposing and reassembling device which may be used to transmit and receive subject matter characteristics of images.

5 One of the objects of my invention is to provide a device with stationary parts arranged to cause elementary portions of light flux and groups of elementary portions of magnetic flux to become co-operatively associated to thereby 10 control the transfer of subject matter characteristics of images from one place to another.

Another object of my invention is to provide means whereby subject matter characteristics of images will be usefully transferred from one 15 place to another place by sequentially analyzed elementary portions of a beam of plane polarized light during the reversal and neutralization of adjacent elementary magnetic flux fields to form a resultant field in a common flux path.

20 Still another object of my invention is to provide means whereby subject matter characteristics of images in the form of trains of light energy will be associated with scanning trains of magnetic energy to thereby co-operate therewith 25 to cause the transfer of the said image characteristics from one place to another place.

A further object of my invention is to provide 30 a circuit organization element constituting a magnetic light decomposing cell and arranged magnetically to sequentially and progressively decompose a beam of normal plane polarized light into a plurality of elementary portions each with the said normal plane polarization at the instant of decomposition and in accordance with 35 the characteristics of a single scanning current.

An additional object of my invention is to provide 40 means whereby a beam of light may be magnetically separated in a progressive sequential manner into a plurality of elementary portions periodically repeated as a function of the frequency of the said scanning current.

A still additional object of the present invention 45 is to provide a circuit element cell arranged to magnetically, sequentially and progressively rotate the universal plane polarization of elementary portions of a beam of plane polarized light through parallel planes.

A still further object of my invention is to provide 50 means including a conductor mesh network formed by a plurality of grid portions immersed in a dielectric magnetically affected at elementary portions by fields created by subject matter characteristic current to thereby act to constitute a light valve.

55 The invention also contemplates the employ-

ment of a conductor mesh network including a plurality of mesh grid portions relatively positioned so as to produce elementary magnetic fields in accordance with trains of current impressed on the said grids whereby elementary portions of a beam of plane polarized light will be progressively and sequentially analyzed by the plane rotating actions of the said fields when traversing in a dielectric flux path, and at an analyzing speed determined by the number of reversing elementary analyzing fields produced by the said conductor network and the frequency of the scanning current.

5 In the following description names will be given to parts for convenience of expression, but the names are intended to be as generic in their applications to similar parts as their art will permit.

The invention allows numerous physical embodiments and one type is herein illustrated for the purpose of showing an application of my invention, but it is understood that the showings in the drawing are largely diagrammatic merely being sufficient in detail to show an application of the invention.

20 The present disclosure is a development of the invention described in my co-pending application Serial No. 89,487 filed July 8, 1936.

In application No. 89,487 separate horizontal and vertical conductor grids were employed to produce reversing elementary magnetic fields in 30 flux paths provided by a dielectric in the path of plane polarized light. However, according to application Ser. No. 89,487, each vertical grid network required a vertical scanning current of a certain frequency, and each horizontal grid required a horizontal scanning current of a different frequency. In addition, the light valve action required two vertical networks and a horizontal network.

35 According to the present disclosure, only one network grid cell and one scanning current are required. The one required scanning current may be of commercial frequency now produced in accurate regularity required for the operation of time indicating circuit elements, and thus the scanning current will be at once available in many places.

40 In the drawing:

Figure 1 is a side elevation view of the arrangement of elements including a light decomposing circuit cell constituting a portion of a television transmitting station organization.

45 Figure 2 is a side elevation view of the arrangement of elements including a light valve and light re-assembling circuit cell constituting 50

a portion of a television receiving station organization.

Figure 3 is a front elevation view of a section of a cell network conductor grid.

5 Figure 4 is a front elevation view of the alternate cell network conductor grid portions showing the relative current conducting relations of the grid magnetic flux producing conductor portions to the grid magnetic flux producing current conducting portions of the grid of Figure 3.

10 Figure 5 is a composite front elevation view of the grid network conductor portions of Figures 3 and 4 showing the means for positioning and supporting the conductor portions relative to each other.

15 Figure 6 is an end elevation view showing the method of alternately assembling the different network grid portions of Figures 3 and 4 and also the means for spacing and insulating the said alternate grids from each other.

20 Figure 7 is a top view of the network grid portions when assembled alternately as in Figure 6.

25 Figure 8 is a diagrammatic presentation of the circuit organization means for connecting the flux producing conductor portions of the assembled grid portions of Figures 3 to 7 inclusive.

30 Figure 9 is a schematic diagram of a portion of the conductor network grids of Figures 3 and 4 showing the current reversing action in certain grid portions as indicated by the arrows.

35 Figure 10 is a diagrammatic presentation of the flow of flux producing currents in the portions of the conductor network of Figure 3 as indicated by the arrows.

40 Figure 11 is a diagrammatic presentation of the passage of magnetic flux producing current in the conductor portions of the network grid of Figure 4 as indicated by the arrows.

45 Figure 12 is a diagrammatic presentation of the composite flow of current in the flux producing conductor network grids of Figures 3 and 4 as indicated by the arrows.

50 Figure 13 is a portion of the sectional view of a section of the horizontal conductor portions of Figure 5 taken along the line B-B in the direction as indicated by the arrows.

55 Figure 14 is a vertical sectional view of the grid portions similar to Figure 13 with the magnetic field flux relations indicated by the arrows to show the progressive sequential magnetic flux combining and neutralizing action resulting from the current reversing action shown in Figure 9.

60 Figures 15 and 16 indicate graphically the effect of superimposing the subject matter characteristic image affected current in relative phase opposition on the network scanning current.

65 The magnetic rotation of plane polarization of light is well known and accepted in the art of magneto-optics.

70 The theory of the flow of current through recurrent conductor networks is also well known and accepted in the art.

75 It is also accepted in the art that electric field rotation of plane polarization of light is accompanied by elliptical rotation of the said plane polarization which acts to prevent useful decomposition and reassembly of image subject matter characteristics modulating elementary portions of the said light.

The present disclosure contemplates the employment of single scanning current directed through a recurrent mesh network of two groups of grid conductor portions arranged so as to con-

duct current to create elementary portions of magnetic flux progressively and sequentially reversed during a single alternation of the scanning current and combined as a function of the characteristics of said impressed scanning current. The reversal of polarity of a magnetic field is normally accompanied by absence of any field during such reversal, but in the present disclosure two adjacent fields (one from each group) are always associated in a dielectric flux path in addition or opposition because of said reversal.

5 When the said magnetic fields are equal and in opposition, it is obvious that the said magnetic fields will be neutralized in the common portions of their flux paths, and thus the plane polarization of elementary portions of a beam of light passing through a dielectric in this common path will be rotated out of the original plane polarization when the magnetic fields are in addition and will not be rotated out of the said original plane 10 when the said magnetic fields are neutralized in the said portion of the flux path thus to be combined in other adjacent portions of the paths.

15 When the present disclosure is based on the novelty of providing conductor network means for producing two elementary fields in a common dielectric flux path and varying the fields relative to each other so that they change from a state of addition in the said paths to a state of opposition or neutralization one after the other. If 20 plane polarized light is passed along this path, its plane will be rotated by the additive field effect and this plane polarization will return to the normal plane polarization as the fields approach the neutralized state.

25 If a plurality of elementary portions of plane polarized light are thusly associated with a plurality of elementary magnetic fields produced by imposing a single scanning current on both the groups of conductor portions of a mesh grid network, it is obvious that magnetic flux and light flux may be so associated that a progressive current reversing action and thus an associated magnetic field opposing, adding or neutralizing action 30 will be provided to progressively and sequentially permit the rotated plane polarizations of the said elementary light portions to sequentially return same to the normal plane polarization.

35 The present disclosure also contemplates the production of the elementary portions of network grid magnetic flux with a minimum of electric potential between adjacent flux producing grid conductor portions, and thereby with a minimum of accompanying elliptical plane rotation of the associated plane polarized elementary light portions 40 passing along a dielectric flux path between the said network grid conductor portions.

45 Referring to Figure 1 there is shown a beam of light 116 of proper intensity. A previously exposed and developed record affected film 117 hereinafter referred to as the image to be transmitted is placed in the path of the beam 116 and the film 117 is movable in a conventional manner relative to the said beam by means of the supporting storage rollers 118 and 119 so as to properly image effect 50 the beam 116 to provide an image affected beam of light 20.

55 A light decomposing circuit element cell 21 is provided with water-tight transparent opposite sides, one side including a conventional light polarizing film 22, such as "Polaroid" and the opposite side provided with a light analyzing film 23, such as "Polaroid" positioned so as to analyze polarized light plane polarized by the film 22. The said polarizing and analyzing films are placed 60

in the path of the light beam 116 and the image record affected beam 20 so that analyzed light portions 24 may pass through the rectangular mesh openings of the said network grid conductors when assembled as shown in Figure 5 and thence intercepted as hereinbefore described by the conventional light sensitive circuit element 25 connected to a conventional television transmitting circuit organization (not shown) by means of the leads 26 and 27.

In Figure 2 there is shown a beam of light 28. A combined light valve and reassembling cell 29 similar to the cell 21 of Figure 1 is placed in the path of the beam 28 so that the said light beam may pass through the said cell and thus through the plane polarizing film 30 and the analyzing film 31. The image affected analyzed light portions 32 and these analyzed light portions may be collectively and usefully viewed by the light sensitive element 33 indicated in Figure 2 as a human eye.

In Figure 3 there is shown one of the A network grid portions preferably formed from a sheet of current conducting material such as copper, aluminum or silver or wire of the same material woven in screen or grid form and having main vertical grid conductor portions 44 to 53 and horizontal conductor portions 64 to 69 inclusive. The horizontal and vertical grid conductor portions are preferably formed at right angles to each other to form rectangular openings and as nearly in the same plane as possible if of the woven wire type, and substantially in the same plane if the perforated sheet type.

Figure 4 shows a B conductor screen grid similar to the network conductor grid of Figure 3 except that the horizontal conductor portions 70 to 74 inclusive are horizontally positioned so as to be midway between the horizontal grid portions 64 to 69 when the network grid of Figure 3 is placed on the assembling pins next to the network grid of Figure 4 as shown in Figure 5. This alternate horizontal spacing and positioning of the said horizontal A and B grid conductor portions is clearly shown in Figure 5 when the network grids A and B are alternately assembled on the lining up pins 75 to 78 inclusive. This alternate assembly of network conductor grids A and B may be seen from the side by reference to Figure 6. A plurality of insulating spacers 130 and 131 are also shown in Figure 6. Thus the network grids 34, 36, 38 and 40 and 42 will be similar to the A grids of Figure 3, while the 35, 37, 39, 41 and 43 grids will have horizontal conductor portions similar to the B grids of Figure 4. In this event the alternate grid squares formed by the composite end view (see Figure 3) of the combined conductor portions of the A and B grids will constitute twice as many rectangular flux paths for any magnetic fields created by currents flowing in the said conductor portions as there are openings in the grid form of Fig. 3, especially when the grid network of Figure 5 is submerged in a dielectric material 23-C contained in the cells 21 and 29 of Figure 1 and Figure 2.

Figure 7 shows the top end terminals of the vertical grid conductor portions 45-53 and 54-63 of the A and B grids of Figures 3 and 4 when alternately assembled and spaced as shown in Figures 5 and 6.

All of these vertical conductor portion terminals of Figure 7 will be duplicated of course in a similar bottom view.

The present disclosure therefore is also based

on the use of a varying or alternating scanning current to provide a large number of grid conductor current reversals in the individual horizontal grid conducting portions of the said network during the interval of a single scanning current variation or alternation. If an alternating current is used for network scanning power, these alternating scanning current reversals will be progressive and sequential in the said screen grid conductor portions for each alternation of the said scanning current. If the alternations are periodically repeated as in a commercial 60 cycle power current, the said current reversals will be synchronously effected according to the characteristics of the said power current.

It follows then that the resulting magnetic fields created by these horizontal network grid conductor current reversals will also be synchronously reversed in the dielectric flux paths in the same progressive and sequential manner that the said individual conductor currents are reversed.

This current and associated magnetic reversing action will be more clearly understood by reference to Figure 9. If the positive potential lead 79-A and the negative lead 80-A of Figure 9 are connected to the source of constant potential current and the opposite leads 84-A and 83-A are connected to a circuit element having no potential, the current from the positive lead 79-A will flow in the direction indicated by the arrow and divide in the re-current sections 64 to 69 to flow downward in accordance with the accepted law of current flow in networks. Now, if the positive lead 83-A and the negative lead 84-A are connected to the said source of constant potential current and the leads 79-A and 80-A are connected to a circuit element normally of no potential, the currents from the positive lead 83-A will divide in the re-current sections 64 to 69 to flow upward in accordance with the said law of flow of currents in networks. See "Engineer's Handbook" (Electrical), third edition (Pender, McIlwain), pages 3-02 to 3-19. Note Figures 4, page 3-03; 1, page 3-09; and Figure 1 of page 3-17. Assume that the potential of the scanning current source connected to the network conductor leads 79-A and 80-A is equal electrically to the scanning current source connected to the leads 84-A and 83-A, and that the grid conductor network including the conductor grid portions 64 to 69 inclusive is symmetrical physically and electrically to the said sources. By referring to Figure 8, it will be seen that these feeders are connected to the same source through the leads 81, 82, 85 and 86 in inductive relation with the scanning current source leads 107-108 and 112-113 by means of the windings 104, 105, 109, 110, 106 and 111. The leads 107, 108, 112 and 113 are connected to the same source as hereinafter explained so that the scanning current will be impressed on the two grids groups in relative phase opposition. Thus the flux producing current flowing in the grid portions 64 to 66 will be flowing opposite in relative direction to the current flowing in the grid leads 65 to 69 inclusive.

If the potential of the current supplied to the leads 83-A and 84-A is increased relative to the potential impressed on the feeders 79-A and 80-A then the current flowing in the lead portion 66 will of course decrease in accordance with the accepted laws of networks as stated in Section 2, Paragraph 188 of "Standard Handbook

for Electrical Engineers", to approach a zero value and thence increase in strength in the relatively opposite direction as the potential of the current supplied to the leads 83—A and 84—A is further increased (see Fig. 9).

Now let it be assumed that the potential of the current source connected to the leads 79—A and 80—A gradually decreases to zero strength and that the potential of the current source connected to the leads 83—A and 84—A continues to similarly increase. Eventually all the currents in the grid conductor leads (shown as vertical in Figure 9 only because of the position of the drawing) 64 to 69 inclusive will be reversed one after the other and the reversed currents will then all flow relatively upward as referred to Figure 9. If the potential of the left hand source is now increased as the potential of the right hand source of current is correspondingly decreased the resulting current in the lead 64 will now be reversed, then the current in the lead 65 will be reversed and so on until all of the resulting currents in the portions 64 to 69 inclusive will now be flowing relatively downward with reference to the sheet upon which Figure 9 is placed.

All of these progressive and sequential current reversals of Figure 9 will occur in definite time relation to the potential change of the said current sources.

If a regular alternating current potential is applied to the said current sources 83—A and 84—A and 79—A and 80—A so that the potential of one current source is at a maximum as the other current source potential is at a minimum, then the said grid conductor current reversals in the A grid portions 64 to 69 of Fig. 10 inclusive will in effect collectively constitute a moving current reversing action, moving across the grid opening of Figure 5 periodically repeated according to the characteristics of the said alternating scanning current. The resultant magnetic flux field changes created by these scanning current reversals will also collectively constitute a moving field reversing action moving across the opening of the grid in synchronism with the said current reversals.

If a grid network of current conducting portions as shown in Figures 3 to 7 inclusive is arranged to alternately include a plurality of the A (Fig. 3) and B (Fig. 4) grid portions assembled as shown in Figures 3 and 4 and 9 then a plurality of moving of current reversal action and the resulting action of magnetic flux reversals in effect will be obtained. The main scanning network may be formed with many grid conductor portions in parallel relation as shown in Figure 9, or these grid conductor portions may be formed in a series-parallel grid each including a plurality of conductors as shown in Figures 3 and 4, and as many A and B grid portions as necessary may be used.

While either method of forming the grid network may be employed, the series-parallel arrangement and operation will be explained for the purpose of this description.

In Figure 10 there are shown only four of the vertical grid conductor portions 46, 47, 48 and 49 of the network grid of Figure 3 hereinbefore designated as the A grids. All of the vertical grid portions are assumed to be electrically symmetrical to the current sources connected to the leads 79—A and 80—A and also the leads 83—A and 84—A, and the potential of the said current sources are at first assumed to be equal. Thus an equipotential region will exist in the

horizontal network grid conductors of Figures 3 and 10 in the same manner that an equipotential region exists between portions 66 and 67 of the network portions of Figure 9, and equipotential points in the vertical grid conductors will move along with this equipotential grid region in accordance with the theory of networks as known and accepted in the art.

Now the leads 79—A, 80—A, 79—B and 80—B of Figures 10 and 11 are assumed to be connected to the same current source BA as shown in Figure 8. Also the leads 83—A, 84—A, 83—B and 84—B in the same manner are connected to the same source. The leads 118, 119, 126 and 127 are connected to the positive pole lead 93 of the constant current source BA, and the leads 120, 121, 128 and 129 are connected to the negative pole lead 92. Normally equal constant currents will flow through all these leads. The varying current source C is connected to the leads 113—A and 107—A and to the leads 107 and 113 connected to the primary windings 106 and 111. Thus the varying current will be superposed on the leads 81 and 86 in an opposite direction to its superposed flow in leads 82 and 85. In this event these component currents will be inductively neutral to the image current circuit including the leads 91 and 102 connected to the image current source I connected to the input leads 91—A and 102—A. Thus any change in the potential of the scanning current source will be relatively the same in all the said scanning current leads. When these leads are connected to the network grids of Figures 10 and 11 as shown current will flow in opposite directions in adjacent vertical conducting portions as shown by the arrows of Figures 10 and 11. Thus if the sources of scanning current are all equal and constant, two stationary equipotential network regions will exist, one in each A grid network and one in each B grid network.

These equipotential regions will also exist in the same relative position in all the other A and B grids alternately assembled to constitute the said scanning network. The A set of equipotential grid regions will all be in line horizontally in the path of the light beam 116 in cell 21 of Figure 1 and also light beam 28 passing through cell 29 of Figure 2. The equipotential portions of the B grids will in like manner also be in line in the path of the said beams. Also it should be noted that the said equipotential portions of the B grids will not be in the path of the same elementary horizontal portions of plane polarized light as the horizontal equipotential line of regions of the A grids, but the two horizontal parallel lines of equipotential regions will be relatively very close to each other, for example, about the distance equal to the space between conductor portions 66 and 72 of Figure 12. This is true because the A and B grids are slightly out of symmetry electrically with respect to the current source as hereinafter stated.

A composite section of the said equipotential regions when the said impressions are equal will normally be in the center electrically of the network.

In the composite network of Figure 10 it will normally be found in the horizontal train of squares formed by the alternate grid conductor portions 66, 47, 67 and 48.

This situation may be explained as follows. In Figure 11 there are shown four of the vertical leads 56, 57, 58 and 59 of the grid network of Figure 4. The conductor portions are all elec-

trically and collectively symmetrical to the scanning current source in the same manner as shown for the grid of Figure 10 but the resistance value of the lead of the horizontal conductor portion 70 of Figure 11 to the source of the scanning current is not the same as the resistance value of the lead 64 of Figure 10 to the said source.

Because of this difference in resistance values of the leads the equipotential region of the B grid 10 of Figure 11 will not coincide with the equipotential region of the A grid of Figure 10 when they are alternately assembled as shown in Figure 6, and the current in a horizontal conductor portion 15 of a grid of one of the groups will flow opposite magnetically to the current flow in an adjacent conductor portion of one of the grids of the other group as shown in Figure 12 and on the supports 15 and 71.

Now let it be assumed that this equipotential 20 regional displacement is such that current reversals (see Figure 9) occur first in the A grids and then in the B grids. Then the said current reversals would rapidly occur in an alternate manner first in an A grid and then in a B grid 25 when a varying potential is applied to the network as hereinbefore described.

If the potential of the left hand source is now increasing (see Figures 10 and 11) and the right hand source of potential is equally decreasing 30 these grid conductor current reversals will occur alternately in the adjacent horizontal portions grids of Figures 10 and 11 as shown in Figure 12. The current in horizontal portion 66 of the grid of Figure 10 has just been reversed and thus the grid conductor current in the portions 35 66 and 72 of the A and B grids are now flowing in the same relative direction.

With continued variation (as described in the preceding paragraph) of the impressed potential 40 the current of horizontal grid conductor portion 72 of Figure 11 will next reverse and thence the scanning current of portions 72 and 67 will be flowing in the same direction, but opposite relatively to the direction the currents of portions 45 66 and 72 were just previously flowing. With still further potential variation the scanning current in portion 67 will reverse and the currents of portions 50 67 and 73 will flow in the same direction but relatively reversed to the direction of flow of currents just previously existing in the same direction in grid portions 72 and 67. This action will be progressive from one conductor to the next as shown in Figure 9. During a given 55 alternation all the currents in the horizontal portions of all the two groups of grids will be reversed one after the other in horizontal groups in a progressive and sequential manner, and during this reversing action each current in a horizontal A grid group will flow in the same direction as an adjacent current in a horizontal B grid group for an instant of time.

The frequency or number of these A and B group current reversals for a given scanning current alternation will depend on the number of 60 horizontal conductor portions in the grids and the rate of potential change of the scanning current. It is obvious that a large number of current 65 reversals may be obtained during a single scanning current alternation, and that this number will only be limited by the number of A and B horizontal grid current conductor portions. Only one reversal will occur in a given horizontal portion during a scanning current alternation. Therefore while the rate of network current 70

reversals may be very high the change of current in any individual grid conductor portion will be comparatively slow or in synchronism with the scanning current.

The magnetic field flux produced by the network currents flowing in the horizontal grid conductor portions will also be reversed with the said current reversals. As the grid current in the adjacent horizontal portions on each side of the equipotential region normally flows in opposite directions to the direction of the combining currents, the fields created by these adjacent field currents will add magnetically to produce a single field in the common dielectric flux paths between the said grid portions as shown in Figures 13 15 and 14. These individual grid magnetic fields will have the relatively low frequency of the said scanning currents without regard to the progressively elementary field reversing frequency.

The dots of Figures 13 and 14 representing the vertical feeders of the A and B grids actually 20 will be slightly staggered and not in line as shown. In this event the elementary light portion 24 of the light beam 116 or 20 of Figure 1 will not be plane rotated magnetically when passing through the flux neutralized dielectric flux path between the conductor portions 66 and 72, 47 and 48, 57 and 58 of Figures 10, 11, 12 and 14 as shown in Figure 14 (assuming that the potential of the scanning current is constant for this 30 particular instant).

This is true because there is no magnetic flux in the said light path. The magnetic flux from the two grid currents flowing in the same direction in parallel adjacent grid conductors has combined in other portions of their flux paths, but at the instant the said currents are equal no plane polarization rotating magnetic flux is present in the common dielectric flux path through which the said elementary portion of plane polarized light 24 is passing as shown in Figure 14.

If the network scanning current applied to the network grid conductors is now changed or varied as stated so as to cause a relatively downward current reversing action (see Figure 12) 45 then the magnetic fields of the two groups of A and B networks will next be progressively neutralized as shown in Figure 13 and the elementary portion of plane polarized light 24 passing in the common rectangular dielectric path between the conductor portions 72 and 67, 47 and 48, and 57 and 58 will not be plane rotated magnetically because no rotating field flux is present in the path of the light portion 24 of Figure 13 in the same manner that no plane rotating flux was just previously present in the path of the portion of beam 24 in the common path of Figure 14.

The magnetic flux shown by the closed loop 99 of Figure 14 is the combined flux created by the current flowing in the 66 grid conductor portions of Figure 10 and the current flowing in the 72 conductor portions of the grid of Figure 11. In the same manner, the magnetic flux shown by the closed loop 96 of Figure 13 is the combined magnetic flux produced by the current flowing through the 67 conductor portions and the conductor portion. The arrows show that the combined flux 99 is relatively opposite to the combined flux 96.

All of the magnetic fields as 94, 95 and 97 of Figure 13 and 98, 100 and 101 of Figure 14 gradually increase and decrease according to the characteristics of the scanning current applied to the conductor network grids.

Thus the grid current fields relatively behind the current and field reversing region are increasing and the grid conductor currents and associated magnetic flux fields in the path of the said reversing action are decreasing as considered in Figures 13 and 14.

Thus according to the present disclosure, I provide means for alternately combining the flux fields in an extremely rapid manner inside and outside the common dielectric flux paths.

The number of the A and B grids of Figures 3 and 4 that may be used is large. Thus, while the current carrying capacity of the grid conductors is limited by the cross-section, it is obvious that the length of the rectangular dielectric flux path formed by combining all the elementary flux paths in the path of an elementary portion of the said light is unlimited.

The length of the dielectric plane rotating flux path will be determined by the number of A and B grids assembled in line as shown by Figure 6. Thus the number of grid conductors and thereby the flux required in groups to produce the plane rotating fields as shown by Figures 13 and 14 is not limited, and the A and B grids may be alternately assembled as shown in Figures 6 and 7 to increase the common rectangular flux path in the dielectric to the desired length so as to secure the desired angular universal plane rotation of all the elementary plane polarized light portions except the analyzed portion.

It is an accepted fact that the magnetic plane rotation of light is proportional to the strength of the flux and the length of the dielectric flux path. The magnetic flux in the paths on either side of the neutralized flux path is increased by such neutralizing action. Note lines 98 and 99, and 100 and 101 of Figure 14. The flux will be neutralized for any intensity, but the greater the intensity, the greater the intensity of the flux in the paths adjacent the said neutralized path. Thus the present device provides a scanning device by means of which a sharp spot of analysed light may be obtained. This is true, since there is no rotative effect in the neutralized flux path and a definite rotative effect in the adjacent paths. Furthermore, any reasonable number of A and B grid conductor portions may be used and the length of the dielectric flux path proportionally increased. The magnetic flux created in all these conductor portions are added in their rotative effect in the portions adjacent the said neutralized portion. If 100 grids are used, then two groups of 50 conductors portions each will outline the rectangular neutralized path. The magnetic flux created by current carried by these groups of successive conductors will be added in the adjacent flux paths, and no flux will exist in the said neutralized path. Thus no plane rotation will occur in the said neutralized path, and a comparatively great rotation will occur in the said adjacent paths. It should be noted that the analyser will pass only light with the original plane polarization. The only elementary portion of the dielectric without magnetic flux (at any time) is the said neutralized portion. Thus according to the present disclosure, I provide a scanning device which produces a sharper spot of scanning light than has been possible with any device as now known in the art. In the known devices as the potential on the Kerr cells decreases a decreasing amount of light will pass through the analyser. In the present device there is no decrease of potential on the cell as a unit, because the constant current increases as

the varying current decreases. The variation of the scanning current potential does not affect the amount of light passed by the cell, it only moves the spot of light along its scanning path as hereinbefore described.

It will be obvious that with a change in strength of the network scanning current impressed on the network of all the magnetic fields created in the dielectric flux paths are varying in intensity, and that at least one group of fields is always either at, near or just by its reversing period.

Thus it will be understood that all adjacent groups of horizontal flux fields as shown in Figs. 13 and 14 progressively arrive at equal flux intensities in a sequential manner so as to combine and form the flux fields as shown as loop 96 of Figure 13 and 99 of Figure 14. In this event, no plane polarization rotating magnetic flux will exist in the dielectric flux paths of light portions 24 of Figures 13 and 14. At the same time, this combining action will increase the magnetic flux density of the adjacent light flux paths because the magnetic flux of loops 95 and 96 and 96 and 97 of Figure 13 combine in a common path to rotate the plane polarization of the elementary portions of light adjacent to portion 24, and thus sharp and clearly defined analyzation of subject matter characteristics is provided according to the present disclosure.

No current reversals will occur in the vertical grid conductor portions (see Figure 9) and the magnetic flux produced will alternate in relative direction from grid to grid so that all the elementary rotations of plane polarization by the fields produced by the scanning currents of the vertical conductors of the A grids of Figure 10 will be equalled and in effect neutralized by opposite plane rotation of the plane polarization by the fields produced by the currents flowing in the vertical portions of the B grids of Figure 11.

In the normal operation of the scanning network, it is contemplated to assemble the A and B grids so that the vertical conductor portions will be as close as physically and electrically possible. Thus, the space between adjacent vertical conductors will be very narrow, and in some applications the space will be filled with a non-magnetic material to keep the grid conductor portions insulated from each other.

The space between the horizontal conductors is comparatively large and the flux path for the magnetic flux created by the horizontal current will be entirely in a flux conducting dielectric 23—C.

In addition, the network is so formed as to afford circulation of the dielectric between the spaces between horizontal conductors, and with proper design of the cells 21 and 29 a continual circulation of the dielectric may be provided through the said network to thus conduct heat and equalize all portions of the network groups.

During the interval of magnetic field addition or combining action as shown by the combination flux field loops 96 and 99 of Figures 13 and 14 the elementary portions 24 of plane polarized light passing through the rectangular openings collectively formed by the grid conductor portions will not be plane rotated and will thus be able to pass through the light analyzing film 23 of Figure 1 and 31 of Figure 2 with the original plane polarization. The films 23 and 31 are assumed to be set to analyze plane polarized light in its normal or original polarizing plane of the polarizing films 22 and 30 of Figures 1 and 2.

When the impressed scanning current is of proper wave form and frequency the grid conductor field current and field neutralizing action and thus the said sequential and progressive analyzing action of the reversing and neutralizing fields will collectively appear visibly in the analyzed elementary portions of light in effect as a moving portion of light. The analyzed light will move along a pre-determined path in a transverse manner periodically repeated according to the characteristics of the said network scanning current and in synchronism with its alternations.

When the proper scanning current is employed, the light beam 116 (or the image beam 20) of Figure 1 will be progressively decomposed into elementary normal plane polarized portions 24 of Figures 1, 13 and 14 by the sequential analyzing of the light analyzing film 23 and then in- 15 tercepted by the light sensitive circuit element 25 forming a portion of a television transmitting system (not shown).

If the previously exposed and developed record film 17 is positioned in the path of the beam (either before or after analyzing) 116 as shown in Figure 1, these elementary plane polarized portions 24 will thus be image characteristic affected light portions and the corresponding electric currents produced by the known action of these analyzed image modulated elementary light portions 24 on the light sensitive element 25 will also be image modulated electric currents and may be transferred to an external circuit by the leads 26 and 27.

If the image film 17 is properly moved on the rollers 18 and 19 forming a portion of a conventional motion picture device (not shown) in synchronism with the alternations of the network scanning current impressed on the network A and B grid conductors, then a series of trains of image affected electric currents will be produced in the transmitting circuit system of which the light sensitive element 25 is a portion.

It is of course obvious that the image to be transmitted may be directly scanned by placing the said image in the path of the beam 116 so that the reflected image affected elementary portions of the beam 116 will pass through the cell 21 as beam 20.

Thus, according to the present disclosure, I provide means for magnetically and progressively decomposing a beam of image modulated plane polarized light into a plurality of elementary normal plane polarized portions, and thence transferring these image affected portions of light into corresponding electric currents.

Only one scanning current of comparatively low frequency is required, and this scanning current may be obtained from commercial distributing systems or by conventional space or wire transmission from a remote point.

These trains of image modulated elementary light portions are thus intercepted by the element 25 and corresponding trains of image currents are transmitted by space or wire and received at the television receiver (not shown) of which the elements of Figure 2 are a portion as hereinbefore stated.

After the transmitted image modulated subject matter currents are obtained from the receiving station circuit organization (not shown) they are delivered to the network grids of the combined light valve and reassembling cell 29 of Figure 2.

A method of connecting the sources of the scanning current and the sources of the subject mat-

ter characteristic current to the network grids of cell 29 (and 21) is shown in Figure 8. This circuit applied to the network of cell 21 of Figure 1 except that normally there would be no subject matter characteristic current employed in the decomposition of a beam of light as 116 into elementary portions such as 24.

According to the present disclosure, the scanning current may be applied to the network grids in any suitable manner so long as it acts to progressively reverse all the individual currents in the A and B groups of horizontal conductor portions in a sequential manner according to the characteristics of the said scanning current.

For the purpose of this description, let it first be assumed that a constant potential source of current is connected to the leads 92 and 93 of Figure 8. Thus constant current will equally divide at the junction of the leads 82 and 85 to equally flow through the grid supply leads 79-A, 79-B, 83-A and 83-B as indicated by the arrows of Figures 8, 10, 11 and 12 and after flowing through the A and B grid conductor portions will return by way of the leads 80-A, 80-B, 84-A and 84-B to again unite at the junction of the leads 81 and 86 to thence return to the source through the lead 92.

If the scanning grid network is symmetrical physically and electrically the resulting region of equipotential will then be positioned in the electrically central rectangular light path opening (see portions 66 and 67 of Figure 9).

All other rectangular light path openings filled with the said dielectric material 23-C will constitute common magnetic flux paths containing plane rotating magnetic flux (see Figures 13 and 14) and thus only the elementary light portions of plane polarized light 24 passing through this central flux neutralized path will have the normal or original plane polarization (unrotated) to enable it to pass the normal plane analyzing film 31 of Figure 2 (or film 23 of Figure 1).

This single analyzed elementary portion of light with normal plane polarization is indicated by the parallel dotted lines in the 66, 72, 47, 48 and 45 the 66, 72, 57, 58 composite square of Figure 12.

In normal operation, a stationary portion of analyzed light will be visible when only the constant potential current alone is impressed on the alternate A and B grids of the network, and this spot or point of light will be stationary within limits with variation of the potential of the constant current source because of the similar variations in all the network conductor portions.

This is true because there is no magnetic flux in the said analyzed elementary light portion path as hereinbefore described. Any variation of constant current potential would merely change all the currents in the grid conductor portions to the same extent and thus would merely rotate the plane polarization of the elementary light portions to the same extent, but the position of the point of analyzed light will not change. If the potential of the said constant current source decreased to zero value the neutral area would gradually increase the light portions would eventually be analyzed from all the rectangular openings because there would be no rotating magnetic flux remaining.

The normal network scanning action of the image to be transmitted may be considered for the purpose of this description as starting with an elementary portion of light 24 analyzed from the electrically and physically central flux path

(see Fig. 12) of the circuit element cell 24 of Figure 1.

In operation let it be further assumed that the alternating network scanning current is supplied to the leads 107, 108, 112 and 113 so that the said scanning current will flow through the primary inductive windings 101 and 106 to thereby induce a similar scanning current in the secondary windings 109, 110, 104 and 105.

- 10 In this event the induced scanning current will oppose the constant current in the leads 82 and 86 and add to the constant current in the leads 81 and 85, and a component current reversing action will start in the horizontal grid conductor portions as described for the means of Figures 9, 12, 13 and 14. Elementary portions of the image modulated light beam 26 of Figure 1 will thereby be progressively analyzed by the film 31 with normal plane polarization in a sequential manner 15 to collectively appear visibly as a moving spot of light moving transversely with two modes of motion to the (say) lower right rectangular flux path of Figure 5 as the said scanning current reaches a maximum positive value and thence 20 returning along the same zig-zag path to the said central symmetrical position as the alternation of scanning current decreases to a zero value. As the following negative alternation of the said scanning follows to increase to a maximum in the 25 opposite direction the moving point will continue along its path to the upper left rectangular flux path of Figure 5 to return to the said central position of Fig. 12 as the negative scanning alternation decreases to a zero value.
- 30 35 Thus all the elementary portions of the image affected beam 26 of Figure 1 passing along the rectangular flux paths formed by the network grid conductors will be analyzed for a given cycle of the alternating scanning current.
- 40 It should be noted at this time that the method of superimposing the alternating scanning current on constant potential currents obtains a scanning current with a minimum potential on one portion of the grids as it is a maximum at another grid portion is equivalent to the method as hereinbefore assumed for the purpose of this description.

The method of transmitting the subject matter characteristic currents to the receiving station 50 has been hereinbefore described and it should now suffice to state that if the image of the film 17 of Figure 1 is changed in synchronism with the alternations of the scanning currents supplied to the cells 24 and 29 trains of subject matter characteristic current will be available so as to be imposed on the network grids of the cell 29 in the same relative manner.

According to the present disclosure, this image subject matter current is amplified in any conventional manner and delivered to the leads 91, 102, 103 and 104—A of Figure 8 preferable in a manner so as to flow through the radio frequency transformer windings 88, 87, 89 and 90 and thus induce similar current in the windings 114, 115, 116 and 117 whereby subject matter current will flow in the leads 118, 119, 120 and 121 and also in the leads 126, 127, 128 and 129 so that the induced image subject matter current will be superimposed on the network scanning current 60 in relative phase opposition in the conductor portions of the alternate A and B grids. That is, the subject matter current will aid the said scanning current in (say) the group of grids 34, 36, 38, 40 and 42 and will oppose the said scanning current in the group of grids 35, 37, 39, 41 and 43. Dur-

ing a given instant the alternating scanning current will be decreased in lead 79—A as it is correspondingly increased in lead 17—B when the currents are flowing as indicated by the arrows of Figures 8, 10 and 11.

The effect of such relative increase and decrease of network scanning current in alternate grid conductor portions will be to relatively slow up the current (and associated field flux) reversing action of the horizontal conductors as 64 to 10 69 inclusive of Figure 10 as the current reversing (and associated flux) action is accelerated in the horizontal grid conductor portions 73 to 74 inclusive of Figure 11.

When the image subject matter characteristic 15 is superimposed on the said scanning current the flux neutralizing action will no longer occur in accordance with the characteristics of the said scanning current alone, but will be additionally affected due to the superimposition of the said 20 subject matter current to affect the resultant magnetic field reversing action and field neutralization so as to cause in effect a blinking action of the moving spot of light (analyzed) in accordance with the combined characteristics of the 25 scanning current and the said subject matter current. In other words the moving spot of light will be varied in intensity in accordance with the characteristics of the subject matter current as it moves along its transverse path in accordance 30 with the characteristics of the said scanning current.

When the image subject matter characteristic current is not present or impressed on the network conductors of the cell 29 of Figure 2 the 35 analyzed elementary portions of the light beam 28 will progressively appear in predetermined sequence in accordance with the characteristics of the scanning current as hereinbefore described.

When the said image subject matter current is 40 impressed on the scanning current as hereinbefore described the elementary portions of the beam 28 of Figure 2 will progressively appear as analyzed beam 32 modulated by the said trains of subject matter characteristics of the image fixed on the 45 film 17 of Figure 2. In the event of a succession of images as hereinbefore stated the beam 31 will be modulated in accordance with the characteristics of the said images.

The effect of the opposing and aiding action of 50 the subject matter characteristics image current will be more clearly seen by reference to Figures 15 and 16. If zero potential is indicated by the line 125, then the curve 122 will represent normal potential of the scanning current. The subject 55 matter currents are represented by the curves 123 and 124.

If the subject matter current 123 is superimposed on the scanning current to aid the same, the scanning current will be increased to follow 60 the potential line 123—B of Figure 16. If the said scanning current opposes the said subject matter current then the potential line of the said scanning current will be decreased to the line 123—A of Figure 15.

It should be noted at this point, that the blinking effect caused by the subject matter current is an image characteristic modulation of the spot of analyzed light normally moving in a uniform manner with two modes of motion in a path 70 periodically repeated in accordance with the characteristics of the said scanning current.

If the acoustic and visual actions of the image are both recorded on the movable film 17 of Figure 1 as shown in Figure 7 of my U. S. Patent 75

Serial No. 1,647,652 issued November 1, 1927, then trains of visual action characteristic current and trains of acoustic action characteristic current will alternately be superimposed on the said scanning current supplied to the network of Figure 2.

In this event the sequentially appearing analyzed elementary portions of polarized light as beam 32 of Figure 2 will be alternately modulated with trains of image acoustic action characteristics and trains of image visual action characteristics.

No change in the cell 21 of Figure 1 or cell 29 of Figure 2 will be necessary for the sequential transmission of trains of visual and acoustic action characteristics, and the said alternate trains of visual and acoustic actions may be superimposed in alternate sequence (in the case of space transmission) on the same wave-length as shown and described in my U. S. Patent application Serial No. 483,922 filed September 23, 1930.

These alternate trains of visual and acoustic action characteristics will be received at the television receiving station of Figure 2 in the same manner as for single continuous trains of visual or acoustic actions as hereinbefore described, and without any change in the cell 29. The analyzed beam 32 will however be alternately modulated with these visual and acoustic characteristics and means for transferring the acoustic actions into sound waves will be required. A method is shown in my U. S. Patent application Serial No. 483,922 filed September 23, 1930. Figure No. 3 of this application shows a sound reproducing element 243 connected to a light sensitive element 233 placed in the path of the portion of the acoustic action modulations of the beam from the film portion Sx as the visual action modulated portion of the light beam is usefully viewed by the figure shown. In Figure 1 of this same application there is shown a method of recording the visual and acoustic actions of images in proper synchronism on the same film.

It will be understood that I am fully aware that many conventional light and current affecting elements could have been added to the drawing and included in the description without departing from the spirit of the invention.

Therefore, while I have shown and described and have pointed out in the annexed claims, certain novel features of my invention, it will be understood that various omissions, substitutions and changes in the form and details of the device illustrated or in its operation may be made by those skilled in the art without departing from the spirit of the invention.

Having thus described my invention, I claim:

1. In a light valve, a source of reference current, a source of scanning current, a source of image action current, means comprising a plurality of parallel screen mesh networks formed with parallel conductors arranged in turn to form similar square light openings alternately offset vertically and in line horizontally for progressively separating plane polarized light into elementary portions as a function of the cooperative action of two groups of elementary magnetic fields positioned in succession in a dielectric in the path of the said light, means providing the said light, means constituting the said dielectric, said separating means including conductors for collectively conducting current for creating the said magnetic fields so that adjacent lines of successive fields of the said two groups positioned in the path of the same elementary portion of the

said light will be alternately reversed according to component scanning current from two of the said sources, said reversals occurring in parallel transverse paths relative to the said light in accordance with the combined characteristics of the reference and scanning currents, circuit means for conducting the said component current from the said sources, additional circuit means for conducting current from another of the said sources for superposing image characteristic fields on the groups of component scanning fields thereby to differentially vary the intensity of the said elementary light portions as they are sequentially separated by the co-operative action of the scanning fields according to the component characteristics of the said image field and the scanning field, means for analysing the light portions, and image screen means for viewing the said portions.

2. In a television device, a source of constant current, a source of varying scanning current, a source of image characteristic current, means providing a source of light, means for polarizing said light, current conducting network means including alternately positioned groups of recurrent sections each with repeated common connecting portions connected to the source of constant current for conducting current from same for creating a plurality of identical groups of elementary magnetic fields in dielectric flux paths positioned in the path of the said light, said flux paths arranged in groups, each group approximately in line so as to be alternately offset vertically to the same extent relative to the said light path, means constituting the said dielectric, means for superposing current from the said scanning current source on the said constant current for collectively varying the said groups of fields so that the fields of one group will be individually and progressively combined with an adjacent field of another group in one parallel path after another in timed relation to the scanning current variations in accordance with the characteristics of the resultant component currents in the said network, additional circuit means for superposing a current from the said image current source on component constant-scanning current for additionally affecting the said field combining action in accordance with the characteristics of the component constant-scanning-image current, said image current superposed in relative phase opposition on the currents creating the adjacent fields of the said groups, means for analysing the light portions having original plane polarization after traversing the said flux paths during said combining action, and means for viewing the collective analysis of the said elementary portions of light.

3. In a device of the class described, a source of constant potential current, a source of varying potential current, a source of image characteristic current, means constituting a universal light valve circuit element including a conductor network formed with two groups of grids each including a plurality of horizontal and vertical spaced apart repeated magnetic field producing portions, said vertical portions in line and said horizontal portions alternately out of line relative to a common axis, a container with opposite transparent walls, polarizing films on said walls, said container arranged for positioning the said network within the said container, a dielectric for surrounding said portions, means providing a beam of light and projecting same through the said films and alternately between the said suc-

cessive offset horizontal grid current conducting field producing portions of each of the said groups, circuit means for supplying constant current from one of the said sources in relative opposition in adjacent group portions of the said network, circuit means for superposing an alternating current in relative phase opposition on the said constant current from a second source so as to cause the successive fields produced in the said offset lines to reverse as a set one set after the other in parallel paths in timed relation to the variations of the said varying current, additional circuit means connected to the third source for superposing an image characteristic current on the component constant-alternating currents so as to oppose same in certain horizontal portions of one group as it adds to the currents in similar symmetrical portions of the other group whereby the elementary portions of the said light may be decomposed in accordance with the combined characteristics of the three currents, means for analysing the decomposed light portions, and image screen means for intercepting the analysed portions so as to collectively view the same.

4. In a television receiver, two sources of current including means for supplying constant potential current and varying potential current, means for producing a beam of light, means for plane polarizing the said light, means constituting a conductor network including two identical parallel groups of alternately spaced apart repeated parallel screen grid portions, said groups offset in one direction and in line in another direction relative to the said beam so as to form two light paths, each path outlined vertically by portions of both groups and horizontally by portions of one of the groups so as to form light paths in the path of the said light a dielectric material for surrounding said network, circuit means including means for connecting the said network to the said sources for supplying component flux creating current to symmetrical conducting network portions of each group so that a resultant magnetic field reversing action will occur first in symmetrical horizontal portions of one group and thence in adjacent symmetrical portions of the other group due to the variation of the said component current from the said sources whereby the resultant fields will combine to cause the plane polarization of certain elementary portions of light to remain in the original plane polarization as the plane polarization of other light portions is rotated said field combining action in effect progressively moving along one parallel path after another in timed relation to the actions of the said component current so that one elementary portion of the light will remain in normal plane polarization in accordance with such timed relation, means for analysing the said elementary light portions with original plane polarization, image means in the path of the said analysed light, and image screen means for usefully intercepting the image affected light.

5. In a device of the class described, the combination including two sources of current, one of said sources normally providing constant potential current and the other source normally providing variable potential current network means including grids of conductors in screen mesh circuit relation to form similar screen openings, said screen grids arranged in parallel relation vertically so that the openings will be in a staggered line relation horizontally for conducting a cur-

rent from a first of the said sources to flow in the elementary portions of the said network to thereby create two identical elementary groups of normally constant magnetic fields sequentially of different polarity and progressively varying intensity, dielectric means constituting transparent flux paths for each of the said fields, circuit means for superposing a second current from a second of the sources on the first mentioned current so as to progressively reverse the polarity of the groups of fields in a sequential manner one after the other so that a field reversal will occur first in an elementary flux path associated with one group and thence in a symmetrically similar elementary flux path associated with the other group so as to provide a progressive field reversal action along one parallel path after another in timed relation to the variations of the said varying current, a source of light, means for plane polarizing the said light, means for positioning and supporting the said network portions in the path of the said light, means for analysing portions of the light, image means in the path of the analysed light, light sensitive means for intercepting the image affected light, and means for connecting the light sensitive means to an external circuit.

6. In a device of the class described, a conductor network, a source of scanning current, said network including two groups of identical spaced apart screen mesh portions formed with recurrent sections with common repeated current conducting elements, circuit means for separately connecting each portion of each group to the source of scanning current, said portions including current conducting elements arranged in related square shaped current conducting paths so that the said current will reverse in an element of a square path of one portion and thence in an element of a square path of the other portions to cause a current reversing action along one parallel path after another, said reversing action occurring until the current in all the elements of both groups have been reversed.

7. In a device of the class described, a screen conductor network, two parallel sources of current for supplying constant and varying current, said network including two groups of mesh portions each with recurrent sections with repeated common portions, said sections and said common portions collectively forming a plurality of like related square current conducting paths in each portion of each group, each portion connected through all the other screen portions to the sources of current so that a component current will flow in one direction and thence in the opposite direction in one square path part of the mesh after the other to cause a procession of current reversals in the common portions moving in effect in parallel paths in definite time relation to the characteristics of the said varying current in accordance with the characteristics of the current from the said sources, and means for positioning and supporting the said network and said connections so that the square paths of one group will be positioned out of line with the square paths of the other said group.

8. In a device of the class described, a conductor network, a source of constant current, a source of varying current, a beam of light, means for plane polarizing said light, said network including two groups of parallel conducting screens forming similar rectangular openings alternately disposed in slightly offset relation in the path of the same elementary portions of the said beam,

each of said screens including recurrent sections with repeated common connecting portions in spaced apart parallel relation in the path of the said light, the connecting portions of the groups 5 so related that successions of same lie in lines parallel to the said light a dielectric surrounding the screens, circuit means for impressing a component current from the said sources in like manner on the said groups so as to cause the currents 10 carried by the common portions to reverse one after the other along parallel paths one after

the other in synchronism with the characteristics of the said varying current, means for analysing the light portions after transmission through the said offset openings between portions of the screens and thus the dielectric, means for image 5 affecting the light portions, photoelectric means for intercepting the image affected light to transfer same into corresponding currents, and means for transmitting the currents.

10

HOWARD J. MURRAY.
